ETHYLDECABORANE OR B_5H_9 WITH
MIXED ClF_5 OXIDIZER

ABSTRACT OF THE DISCLOSURE

Liquid rocket propellant systems comprising a fuel, either ethyldecaborane or pentaborane-9, and an oxidizer of ClF_5 mixed with either an iodine oxyfluoride or an iodine fluoride-tetranitro methane mixture.

BACKGROUND OF THE INVENTION

In missile design it is desirable to give the missile the capability of delivering a high payload. This is generally achieved by providing a propellant system that has a high specific impulse, I_s . Additionally, it is desirable that the propellant be relatively dense, so that the missile itself will not be unduly large. A convenient measure of this parameter is density impulse, I_D . The I_D of a propellant system is arrived at by multiplying the I_s of the system and the propellant bulk density. An I_D of greater than 400 g.-sec./cc. is desirable.

It is also desirable to provide propellant systems that are storable under conditions considerably less difficult to maintain than cryogenic. These criteria might be especially critical in, for instance, tactical missile applications.

High specific impulses and high densities have been achieved in storable propellants in the prior art by the use of fuels that are heavily loaded with solid light metals, such as boron, aluminum, and beryllium. While these loadings do meet the requirements of density, specific impulses, and storability, the fuel which results has unfavorable mechanical properties which make pumping and storing difficult.

It is an object of this invention to provide new rocket propellant formulations.

SUMMARY OF THE INVENTION

The rocket propellant system of the instant invention comprises a fuel selected from the group consisting of pentaborane-9 (B_5H_9), ethyl-decaborane (EDB) and mixtures thereof and an oxidizer comprising chlorine pentafluoride and either an iodine oxyfluoride or an iodine fluoride mixed with tetranitromethane.

B_5H_9 and EDB are fuels known to the prior art. If they are oxidized by prior art storable oxidizers, such as inhibited red fuming nitric acid, N_2O_4 , H_2O_2 , or N_2H_4 , a satisfactory specific impulse is achieved. However, the density impulse is low. Generally, the density impulse for the named oxidizers with either B_5H_9 or EDB is below 350 g.-sec./cc. A higher I_D is desirable in missiles of fixed dimensions, e.g. tactical missiles. In the instance of missiles of fixed dimensions, the I_D would be a more pertinent measure of the payload capacity than the I_s .

If the recently discovered high energy oxidizer, chlorine pentafluoride, ClF_5 , is used in combination with EDB or B_5H_9 , high specific impulses, in the range of 298 to 307 sec., are achieved and density impulses of about

2

450 g.-sec./cc. are achieved. These are high, but they can be improved upon.

It has been discovered that a combination of ClF_5 and other oxidizers with EDB and B_5H_9 gives an optimum balance of specific impulse and specific density. The oxidizer mixed with ClF_5 should be either an iodine oxyfluoride or an iodine fluoride mixed with tetranitromethane.

As in the prior art, the oxidizer system and the fuel should be present in about stoichiometric ratios. The proportion of the oxidizer other than ClF_5 in the propellant is a function of the percentage of boron in the fuel used. If only ClF_5 were used as an oxidizer, the boron containing fuel would combine with the ClF_5 to produce BF_3 . However, if oxygen is present in the oxidizer, the boron containing fuel will burn to produce the combustion product BFO. It has been found that the combustion product BFO is more desirable than the combustion product BF_3 since BFO has a lower enthalpy, indicating a higher specific impulse.

An excess of oxygen causes the combustion product H_2O to be formed in preference to the combustion product HF. This is undesirable as the combustion product H_2O indicates a lower specific impulse than the combustion product HF. Consequently, it is preferred that there be one mole of oxygen present in the oxidizer mixture for every mole of boron present in the fuel. As explained above, this maximizes the amount of the combustion product BFO and minimizes the amount of combustion product H_2O . The amounts of IF_5O and FIO_3 are readily calculable from these criteria. In the case of tetranitromethane and IF_5 , the tetranitromethane supplies the one oxygen per boron atom while the dense oxidizer IF_5 is added to increase the specific density of the mixture to a point above the design I_D . In general, an I_D of over 450 g.-sec./cc. is preferred. By proper adjustment of these oxidizer and fuel combinations, high specific impulses and specific densities can be achieved.

DESCRIPTION OF THE PREFERRED EMBODIMENTS

The following examples illustrate preferred embodiments of the novel compositions of this invention.

45

EXAMPLE I

A liquid rocket propellant system is formulated, in weight percent of 22.8% IF_5O , 68.2% ClF_5 and 9% B_5H_9 ; an I_s of 288 sec. and an I_D of 480 g.-sec./cc. are realized.

EXAMPLE II

A liquid rocket propellant system is formulated, in weight percent, of 11.3% TNM, 17% IF_5 , 59.2% ClF_5 , 12.5% EDB; an I_s of 285 sec. and an I_D of 482 g.-sec./cc. are realized.

EXAMPLE III

A liquid rocket propellant system is formulated, in weight percent, of 18% FIO_3 , 62% ClF_5 , 10% EDB, and I_s of 286 sec. and an I_D of 502 g.-sec./cc. are realized.

Since it is obvious that many changes and modifications can be made in the above-described details without departing from the nature and spirit of the invention, it is to be understood that the invention is not to be limited thereto except as set forth in the appended claims.

We claim:

1. A rocket propellant system comprising a stoichiometric mixture of fuel selected from the group consisting of pentaborane-9, ethyldecaborane, and mixtures thereof; and an oxidizer comprising chlorine pentafluoride and either an iodine oxyfluoride or an iodine fluoride mixed with tetranitromethane.
2. The system of claim 1 wherein the fuel is ethyldecaborane and the oxidizer is a mixture of ClF_5 and IFO_3 .
3. The propellant system of claim 1 wherein the fuel is B_5H_9 and the oxidizer is a mixture of IF_5O and ClF_5 .
4. The propellant system of claim 1 wherein the fuel is ethyldecaborane and the oxidizer is a mixture of tetranitromethane, IF_5 and ClF_5 .
